UNITED STATES PATENT OFFICE.

WILLIAM H. BERGER, OF WINONA, MINNESOTA.

DESIGN FOR A TOY DOG.

Application filed May 25, 1922. Serial No. 2,410. Term of patent 3½ years.

To all whom it may concern:

Be it known that I, WILLIAM H. BERGER, a citizen of the United States of America, residing at Winona, in the county of Winona and State of Minnesota, have invented a new, original, and ornamental Design for Toy Dog, of which the following is a specification, reference being had to the accompanying drawings, forming part thereof.

I claim:

The ornamental design for a toy dog as shown.

WILLIAM H. BERGER.

Witnesses:

EARL SIMPSON,
MINNIE WITT.
